STABILIZATION OF ALKYL PHENOL COMPOUNDS

Jacob J. Menn, Martinez, and Edwin G. Wallace,
 Walnut Creek, Calif., assignors to Shell Development Company, Emeryville, Calif., a corporation of Delaware

No Drawing. Application July 28, 1951,
 Serial No. 239,184

12 Claims. (Cl. 260—624)

1

This invention relates to the stabilization of alkyl phenol compounds, it being particularly directed to a process for improving the resistance of said compounds against deterioration in color and odor with age.

The alkyl phenols, wherein at least one of the hydrogen atoms attached to the phenyl nucleus is replaced by an alkyl group, are normally light-colored compounds having a mild odor when freshly prepared. However, many of these compounds take on a definite discoloration when allowed to stand, at the same time acquiring a strong and rather unpleasant odor. This deterioration in quality is particularly manifest in the case of the polyalkyl phenols, many of which, especially the 2,4,6-trialkyl phenols, are employed as oxidation inhibitors in materials where it is important that there shall be no change in the color or odor of the resulting composition.

It is a general object of the present invention to provide a method for improving the resistance of alkyl phenols to deterioration in color and odor with age. A further object is to provide a method of this character which may be effectively employed in the treatment of polyalkyl phenols. The compound 2,6-di-tertiarybutyl-4-methyl phenol, though possessing outstanding inhibitor qualities, is especially susceptible to yellowing and odor-development during storage, and it is a particular object to provide a method for improving the color- and odor-stability of this compound. The nature of still other objects of the invention will be apparent from a consideration of the descriptive portion to follow.

It has been discovered that the stability of alkyl phenol compounds against deterioration in color and odor can be greatly improved by treating said compounds with an organic polybasic carboxylic acid or salt thereof. As a result of this treatment, it is possible to provide alkyl phenol compounds which would otherwise discolor and acquire an unpleasant odor after a short interval, but which are now capable of being stored for many months without exhibiting any appreciable change in color or odor.

2

The polybasic carboxylic acid or salt employed in stabilizing the alkyl phenol compound can be selected from a wide variety of compounds. Representative stabilizer compounds of this type, any 5 one or more of which can be used in the process of the present invention, are sebacic acid, adipic acid, oxalic acid, citric acid, tartaric acid, diammonium citrate, monosodium citrate, disodium citrate, disodium tartrate, monopotassium adipate, dipotassium citrate, diammonium tartrate, and monoammonium tartrate. However, a preferred group of compounds for use in stabilizing the alkyl phenols comprises citric acid, tartaric acid, and the alkali metal and ammonium salts 10 of said acids.

The process of the present invention can be practiced with good effect in the case of any alkyl phenol. Representative starting compounds of this type are o-, m- and p-ethyl phenol, p-propyl 20 phenol, p-isopropyl phenol, p-tertiarybutyl phenol, 2,4-dimethyl phenol, 2-methyl-4-tertiarybutyl phenol, 2-tertiarybutyl-4-methyl phenol, 2-methyl-4-dodecyl phenol, 2,4-ditertiarybutyl phenol, 2,6-diethyl phenol, 2-methyl-6-tertiarybutyl phenol, 2,4,6-trimethyl phenol, 2,6-diethyl-4-methyl phenol, 2,4,6-triethyl phenol, 2,6-di-propyl-4-methyl phenol, 2,4,6-tripropyl phenol, 2,6-diethyl-4-tertiarybutyl phenol, 2-tertiarybutyl-4,6-dimethyl phenol, 2,4,6-tritertiarybutyl phenol, 2,4,6-triisopropyl phenol, 2,4,6-tritertiaryamyl phenol, 2-tertiarybutyl-4,6-ditertiaryamyl phenol, 2-tertiaryamyl-4,6-dimethyl phenol, 2-isopropyl-4,6-dimethyl phenol, 4-methyl-2,6-di-tertiaryamyl phenol and 2,6-di-tertiarybutyl-4-tertiaryamyl phenol. However, particularly good 35 results have been obtained in the treatment and resultant stabilization of the polyalkyl phenols, many of which are given above. These polyalkyl phenols are prepared by conventional processes, the usual method being to heat phenol or an alkylated phenol derivative such as o-, m- or p-cresol with an alkene in the presence of an acidic condensing agent such as sulfuric acid, phosphoric acid, hydrogen chloride or ferric 40 chloride, the alkene attaching to one or more of

the carbon atoms of the phenyl nucleus, depending on the reactant proportions employed. The next step in the process is usually to neutralize the reaction mixture with aqueous caustic solution, following which the neutralized product is washed and, if desired, further purified, as by crystallizing the product one or more times from an alcoholic or other liquid solution. The products so obtained are normally light in color and possess little objectionable odor, though many darken rapidly and develop an objectionable odor as they are stored.

The alkyl phenol compounds are stabilized by treatment with a suitable acid or salt in the presence of a solvent for the stabilizer or for both the stabilizer and the alkyl phenol. When present in the molten condition, the alkyl phenol may itself act as the solvent, though other solvent media such as water, ethyl, methyl, isopropyl and various other alcohols, as well as ethers such as diethyl ether, methyl ether of diethylene glycol and the like, can be used. Thus, the stabilizer compound, in either the presence or absence of a solvent, can be added to a system wherein the alkyl phenol is present in the liquid condition. Again, a solution of the acid or salt can be added to the solid alkyl phenol compound. The details of several available treating methods will be set forth in the examples.

The amount of the stabilizing agent to be employed is susceptible to some variation. Thus, amounts as small as 0.01% of the acid or salt, in terms of the weight of alkyl phenol compound present, have given good results, though preferably there is employed at least 0.05% of the stabilizing additive. Again, good results have been obtained by using amounts thereof as large as 5%, though for reasons of economy it seldom pays to use more than about 1% since any additional benefits so gained do not justify the added expenditure.

It is a feature of the present invention that the stabilizing action exerted by the added acid or salt compound employed persists even though the stabilized alkyl phenol compound is thereafter given one or more of various washings or even recrystallization treatments with solvents which might otherwise be expected to remove any of the acid or salt stabilizer present. This is an advantage since the stabilizer can be added to the alkyl phenol compound at the convenience of the operator, and need not be added during the final treating steps. In some cases the latter are practiced only after the lapse of a considerable period following the original production of the alkyl phenol compound, during which period the phenol might otherwise have deteriorated in color and odor were it not for the stabilization treatment earlier practiced.

The process of the present invention is illustrated by the following examples:

EXAMPLE I

A. A quantity of 2,6-ditertiarybutyl-4-methyl phenol was prepared by alkylating p-cresol with isobutylene in the presence of a minor amount of concentrated sulfuric acid as catalyst. The acid alkylate produced in this manner was then neutralized with aqueous caustic solution and water-washed. The resulting product was then combined with an equal weight of a solvent made up of 85% isopropyl alcohol and 15% water at 60°C. The resulting solution was then cooled to room temperature, thereby crystallizing out the alkyl phenol. These crystals were recovered,

washed with fresh quantities of the isopropanol solvent, and air dried. As indicated in the table which follows Example IV, the crystalline product so obtained, which was originally white in appearance, and had a mild odor, became progressively darker as it was allowed to age. At the same time, its original mild odor changed in character and grew progressively more unpleasant.

B. Companion operations were conducted under the same conditions as those described in the foregoing paragraph, except that here the neutralized alkylate was washed for a period of 30 minutes not with water, but with a hot (80°C.), 1% aqueous solution of citric acid, the amount of wash solution employed in each case being such that the quantity of stabilizer present amounted to 0.3% by weight of the 2,6-ditertiarybutyl-4-methyl phenol. As will be seen from the table, the crystalline products which had earlier been washed with citric acid solution were little changed in either color or odor by the storage period.

EXAMPLE II

In this operation fresh crystals of 2,6-ditertiarybutyl-4-methyl phenol prepared in the manner described in Example I, paragraph A above, were slurried at room temperature with one-third their weight of a 0.1% solution of citric acid in a solvent made up of 85% isopropyl alcohol and 15% water. As indicated by the data presented in the table, the product recovered from the resulting slurry had been completely stabilized.

EXAMPLE III

In this operation the untreated crystals prepared as described in Example IA were placed in a Buchner funnel where they were washed at room temperatures with one-sixth their weight of a 0.1% solution of citric acid in a solvent containing 85% isopropyl alcohol and 15% water. As indicated by the data presented in the table, complete protection against deterioration in the color or odor of the alkylated phenol was afforded by the treatment.

EXAMPLE IV

In this operation the 2,6-ditertiarybutyl-4-methyl phenol product obtained on neutralizing and water-washing the 2,6-ditertiarybutyl-4-methyl phenol prepared by treating p-cresol with isobutylene in the presence of sulfuric acid, was mixed with 20% by weight of a solvent made up of 85% isopropyl alcohol and 15% water, the resulting liquid being maintained at 80°C. for ½ hour. At the end of this period the organic layer was separated and then cooled with stirring, to room temperature, to crystallize out the alkyl phenol. The crystalline product so obtained was twice washed with alcohol-water solvent, after which the crystals were air-dried for two days. As indicated by the data present in the table, the crystalline product obtained in this manner rapidly deteriorated with age.

In companion operations conducted under otherwise the same conditions as described in the preceding paragraph, various stabilizing agents, including citric acid, tartaric acid, and diammonium citrate, were introduced along with the alcohol-water solvent media from which the product was crystallized. As shown in the table, each of these additives effectively stabilized the product against deterioration in color and odor.

TABLE

Stability of 2,6-ditertiarybutyl-4-methyl phenol

Example No.	Stabilizer	Percent ¹	Gardner Color No. ² of Melt After—					
			0 weeks	2 weeks	4 weeks	8 weeks	14 weeks	18 weeks

¹ Percent stabilizer employed, based on weight of 2, 6-ditertiarybutyl-4-methyl phenol present.

² On the Gardner Color Scale, No. 1 corresponds to a nearly water-white liquid. No. 5 is a very pale yellow, and No. 10 is a deep yellow. This scale is defined in the reference work by Gardner and Sward, "Physical and Chemical Examination, Paints, Varnishes, Lacquers, Colors," 1950 ed., page 9. Published by Henry A. Gardner Laboratory, Inc., 4723 Elin St., Bethesda, Md.

The claimed invention is:

1. The method for improving the color- and odor-stability of an alkyl phenol having an alkyl group of at least two carbon atoms, comprising treating said alkyl phenol with at least one stabilizer compound selected from the group consisting of the polybasic carboxylic acids and the salts of said acids, the amount of said treating agent being 0.01% to about 1% by weight of said alkyl phenol.

2. The method of claim 1 wherein the treatment is effected in the presence of a solvent for said stabilizer compound.

3. The method of claim 1 wherein the alkyl phenol is a polyalkyl phenol.

4. The method of claim 1 wherein the alkyl phenol is 2,6-ditertiarybutyl-4-methyl phenol.

5. The method of claim 1 wherein the alkyl phenol is 2,6-ditertiarybutyl-4-methyl phenol and the stabilizer compound is citric acid.

6. The method of claim 1 wherein the alkyl phenol is 2,6-ditertiarybutyl-4-methyl phenol and the stabilizer compound is tartaric acid.

7. The method for improving the color and odor-stability of an alkyl phenol having an alkyl group of at least two carbon atoms, comprising crystallizing said alkyl phenol from a solution containing 0.01% to about 1%, based on the weight of said alkyl phenol, of a polybasic carboxylic acid.

8. The method of claim 7 wherein a ditertiary

alkyl-methyl phenol is crystallized from an aqueous isopropyl alcohol solution of an aliphatic dicarboxylic acid.

9. The method for improving the color- and odor-stability of an alkyl phenol having an alkyl group of at least two carbon atoms, comprising treating said alkyl phenol with 0.01% to about 1% by weight of said alkyl phenol of a hydroxy polybasic carboxylic acid.

10. The method for improving the color- and odor-stability of an alkyl phenol having an alkyl group of at least two carbon atoms, comprising treating said alkyl phenol with 0.01% to about 1% by weight of said alkyl phenol of a polybasic carboxylic acid salt.

11. The method of claim 10 wherein the polybasic carboxylic acid salt is an alkali metal salt.

12. The method of claim 10 wherein the polybasic carboxylic acid salt is an ammonium salt.
